John F. Rathbone, Albany, New York.
Letter Patent (Design No. 157) dated 23 Oct. 1857.

The schedule referred to in these Letters Patent and making part of the same.

Be it known that I, John F. Rathbone of the City of Albany and State of New York have produced a new ornamental design for an airtight stove, and I do hereby declare that the aforesaid accompanying drawing is a full and accurate delineation of a stove constructed after my design, the side and back, not shewn, being similar to and symmetrical with the side and front as represented, except that the back has the usual opening & flange for the applying and fitting the pipes or smoke

Des. 157

flue to the stove.

What I claim as my invention, and desire to secure by Letters Patent, is the combination and arrangement of ornamental figures and forms represented in the accompanying drawing, and by the model plates herewith deposited in the Patent Office, making an ornamental design for an Air-tight Stove.
